UNITED STATES PATENT OFFICE.

JOHN B. JOHNSON, OF SAN FRANCISCO, CALIFORNIA.

MOP.

1,147,174.

Specification of Letters Patent. Patented July 20, 1915.

Application filed October 28, 1914. Serial No. 868,994.

To all whom it may concern:

Be it known that I, JOHN B. JOHNSON, a citizen of the United States, residing in the city and county of San Francisco and State 5 of California, have invented new and useful Improvements in Mops, of which the following is a specification.

This invention relates to mops or scrubbing devices and the like.

10 One of the objects of the present invention is to provide a simple, substantial, cheaply manufactured scrubbing mop, and in particular to provide a head of novel construction in which the mop may be securely fastened.

15 Another object is to provide means whereby the mop section proper may be quickly applied to the head or detached therefrom.

Further objects will hereinafter appear.

20 The invention consists of the parts and the construction and combination of parts as hereinafter more fully described and claimed, having reference to the accompanying drawings, in which—

Figure 1 is a front view of the mop. Fig. 25 2 is a side elevation of leg 6, showing the locking lever in position. Fig. 3 is a front view showing the locking lever and chain in released position. Fig. 4 is a cross section on line 4—4, Fig. 1.

30 More particularly described, A indicates in general the handle, B the mop head and C the mop proper. The head B is constructed of a section of channel-iron which is bent to form a substantial triangular shape. The 35 base section 2 of said triangle, or the end of the mop head, is slightly curved or semicircular and the corners 3 and 4 are rounded, as shown. The upper ends of the head section or legs 6 and 7 are secured to the handle by

40 a bolt 8, while the lower end of the handle projects into a socket 9 secured on the base section 2. A rigid and secure connection is thus made between the handle and mop head.

45 The mop proper is secured to the head by the following means: 10 indicates a chain, one end of which is secured to leg 7, as at 11, while the other end is secured to a locking lever 12. The lower end of this lever is off-

50 set, as at 13, and is adapted to be inserted into one or another of a series of slots 14 cut in the bottom of the channel forming leg 6. The upper end or handle section of the lever is slotted, as at 15, and is adapted to be 55 passed over a threaded projection 16 on bolt

8 and locked against the handle by a thumb-nut 17.

The mop, consisting of a section of fabric or a plurality of interwoven strings, is secured to the head in the following manner: 60 The locking lever is first released to permit the chain to be lowered free of the bottom section 2 of the head (see Fig. 3). The mop is then folded over the chain, as shown. The chain with the mop on it is then pulled 65 up into the channel and the point or offset section of the lever is inserted into the most convenient or closest slot 14 (see the dotted line position Fig. 1). The lever is then swung back in the direction of arrow a until 70 the slotted upper end of same passes over the threaded section 16 of the bolt and is then locked by the thumb-screw 17. The swinging movement of the locking lever, together with the leverage secured, permits a great 75 pull to be transmitted to the chain. The chain, together with the mop, is thus pulled tightly up into the channel where the mop cannot possibly work loose, as it is held both 80 by the pressure of the chain against the bottom of the channel and the clamping action of the sides of the channel against the mop, as at 18 and 19, (see Fig. 4). Furthermore, the rounded corners 3 and 4 of the head 85 permit the mop to be extended sufficiently far around the corners to cover same. This permits the mop to be worked right up against the woodwork and furniture in a room without any danger of marring or scratching same.

90 The materials and finish of the several parts of the mop are such as the experience and judgment of the manufacturer may dictate.

I wish it understood that various changes 95 in form, proportions, and minor details of construction may be resorted to within the scope of the appended claims and that I do not wish to limit myself to the specific design and construction here shown.

Having thus described my invention, what 100 I claim and desire to secure by Letters Patent is—

1. In a mop holder, the combination with a handle, of a head secured thereto, said 105 head being substantially triangular in shape and formed of channel-iron, a chain secured to one leg of the triangular shaped head on which a mop cloth is adapted to be hung, a locking lever secured to the other end of the 110

chain, a plurality of slots formed in the other leg of the head, an offset portion formed on the lower end of the locking lever adapted to be inserted into one of said slots, 5 and means for securing the other end of the lever.

2. In a mop holder, the combination with a handle, of a head secured thereto, said head being substantially triangular in shape 10 and formed of channel-iron, a chain secured to one leg of the triangular shaped head on which a mop cloth is adapted to be hung, a locking lever secured to the other end of the chain, a plurality of slots formed in the 15 other leg of the head, an offset portion formed on the lower end of the locking lever adapted to be inserted into one of said slots, and means for securing the upper end of the lever, said means comprising a bolt extending through the handle over which the 20 lever is adapted to pass and be secured by a wing-nut.

3. A mop head of triangular form with rounded corners adjacent to the horizontal 25 base portion, the base and corners and the legs of the triangle for a distance from the base being channeled with the channel fac-

ing outward, a chain secured to one leg and adapted to lie in the channel, the other leg having perforations adjacent to its juncture 30 with said base, a locking bar to which the free end of the chain is secured intermediate of the ends of the bar, one end of the bar fitting one or the other of the aforesaid perforations as a fulcrum, and means to lock 35 the other end of the bar against the mop head to maintain the tension on the chain.

4. A mop holder comprising a handle, a head secured thereto consisting of an arcuate channel-shaped base section and two legs, a 40 flexible member adapted to be inserted in the channel of the base section to support a mop, said flexible member being secured at one end to one leg, a locking lever to which the other end of the flexible member is secured, and means for adjustably securing said lever to the other leg.

In testimony whereof I have hereunto set my hand in the presence of two subscribing witnesses.

JOHN B. JOHNSON.
